FACIAL VAPORIZER

Douglas W. Anderson, Palatine, Ill., assignor to Hanks-craft Company, Reedsburg, Wis., a corporation of Wisconsin

Filed Apr. 8, 1968, Ser. No. 11,356

Term of patent 14 years

U.S. Cl. D23—148
Int. Cl. D23—04

Fig. 1

Fig. 5

FIG. 1 is a perspective of the facial vaporizer unit;
FIG. 2 is a top plan view of the unit with the hose and
face mask shown in broken lines;

FIG. 3 is a view from one side of the unit;

FIG. 4 is a side view taken at 90° to FIG. 3; and
FIG. 5 is a bottom plan view.

The dominant features of my design reside in the
portions shown in full lines.

For convenience of illustration the hose and face mask
are omitted in FIG. 1 and FIGS. 3 through 5.

I claim:
The ornamental design for a facial vaporizer, as shown
and described.
